UNITED STATES PATENT OFFICE.

ABE L. TEETOR, OF CAMBRIDGE CITY, INDIANA.

DIAMOND-HOLDER FOR STONE-DRESSING TOOLS.

SPECIFICATION forming part of Letters Patent No. 297,728, dated April 29, 1884.

Application filed June 28, 1883. (No model.)

To all whom it may concern:

Be it known that I, ABE L. TEETOR, a citizen of the United States, residing at Cambridge City, in the county of Wayne and State of Indiana, have invented certain new and useful Improvements in Diamond-Holders for Stone-Dressing Tools; and I do hereby declare the following to be a full, clear, and exact description of the invention, such as will enable others skilled in the art to which it pertains to make and use the same.

My invention relates to an improvement in holders for diamonds, borts, carbons, or any other hard substance which is employed for cutting, carving, shaping, or dressing articles in any of the industries wherein they are applicable, the object of the same being to provide a cheap and efficient device that will combine simplicity and economy in construction with durability and efficiency in use; and with these ends in view my invention consists in the parts and combinations of parts, as will be more fully explained and pointed out in the claims.

25 In the accompanying drawings, Figure 1 is a view in perspective of my improved holder. Fig. 2 is a longitudinal sectional view of the same. Fig. 3 is a detached perspective view of the follower, and Fig. 4 is a similar view 30 of the head.

A represents the head of the holder, made of suitable metal, and preferably formed integral with a stem by means of which it is secured to a machine. This head is oblong 35 in shape, and is provided with a central cavity, B, for the reception of the follower C, which latter conforms in shape to the said cavity. The head A is open at one end for the introduction of the follower, and is provided at its opposite end with an opening, a, for the passage of the screw D. The face b of the head is also provided with an open slot, c, communicating with the central cavity, B, for the insertion of the diamond.

45 The follower C can be angular or cylindrical in shape, as shown, and is adapted to snugly fit within the cavity B, so that it will have no unnecessary movement, and is provided centrally with the female-screw-threaded 50 hole for the passage of the screw D. This follower is also provided at one end, around

the central opening, with a series of notches of regular or irregular shapes and sizes, in which the diamonds, &c., rest when the parts are locked in position. The screw D is first 55 passed through the opening a of the head A, and the follower C brought into engagement therewith. By turning the screw, the follower is drawn into the cavity B a suitable distance, and the diamond, bort, or carbon, &c., is 60 placed in position in one of the notches of the follower. Now, by again turning the screw in the same direction, the follower is drawn inwardly and the diamond, &c., firmly clamped 65 between the side of the head A and the adjacent end of the follower. When it is desired to remove or renew a diamond, the screw is loosened and the follower moved out sufficiently to admit of the introduction of the diamond. After the diamond has been placed 70 in position the screw is again tightened. The follower is reversible—that is to say, either end thereof is adapted to hold the diamond in position. If desired, one end can be perfectly plain, while the other can be notched, 75 or both can be notched or plain, as circumstances demand.

This device is exceedingly simple in construction; is durable and effective in use, and can be manufactured at a small initial cost. 80

Having fully described my invention, what I claim as new, and desire to secure by Letters Patent, is—

1. The combination, with a recessed head, of the follower, one end of which is provided 85 with a series of notches, so as to accommodate diamonds of various shapes, and a screw for moving the follower, substantially as set forth.

2. The combination, with a recessed head, of a reversible follower, one end of which is 90 provided with a series of notches, and the opposite end plain, and a bolt for securing the diamond between the follower and head, substantially as set forth.

In testimony whereof I have signed this specification in the presence of two subscribing witnesses. 95

ABE L. TEETOR.
